UNITED STATES PATENT OFFICE.

THOMAS MAHONEY, OF DORRANCE, KANSAS.

GRAIN-STACKER.

1,234,364.

Specification of Letters Patent. Patented July 24, 1917.

Application filed September 20, 1916. Serial No. 121,274.

To all whom it may concern:

Be it known that I, THOMAS MAHONEY, a citizen of the United States, residing at Dorrance, in the county of Russell and State 5 of Kansas, have invented a new and useful Grain-Stacker, of which the following is a specification.

The device forming the subject matter of this application is a conveyer adapted to 10 be used, primarily, in connection with a header, to facilitate the operation of stacking.

The invention aims to provide novel means for moving the conveyer vertically and transversely, to provide novel means for moving 15 the conveyer horizontally and longitudinally, and to provide novel means for shifting the conveyer transversely and in a horizontal direction, longitudinally of the vehicle on which the conveyer is mounted.

With the above and other objects in view which will appear as the description proceeds, the invention resides in the combination and arrangement of parts and in the details of construction hereinafter described 25 and claimed, it being understood that changes in the precise embodiment of the invention herein disclosed can be made within the scope of what is claimed, without departing from the spirit of the invention.

In the accompanying drawing:—

Figure 1 shows in side elevation, a conveyer mechanism embodying the present invention;

Fig. 2 is an end elevation of the structure 35 shown in Fig. 1.

In carrying out the present invention there is provided a vehicle embodying a main frame 1 equipped at its sides and near its ends with depending hangers 2 having 40 outstanding axles 3 on which are journaled ground wheels 4. The numeral 5 designates an auxiliary frame mounted to slide horizontally in guides 6, constituting a part of the main frame 1.

Fixed to and depending from the main frame 1 intermediate the ends thereof are bearings 7 in which is journaled a shaft 8 rotated by means of a crank 9 or otherwise. Secured to the shaft 8 are drums 10. Sheaves 11 are 45 journaled on the hangers 2. The ends of flexible elements 12 are connected with the auxiliary frame 5, the flexible elements being trained around the sheaves 11, and the intermediate portions of the flexible elements 12 being wound around the drums 10.

It will be obvious from the foregoing that

when the shaft is rotated by means of the crank 9, the flexible elements 12 will cause the auxiliary frame 5 to slide on the guides 6, longitudinally of the main frame 1. 60

Fixed to and upstanding from the auxiliary frame 5 at one side of the vehicle is a support 14. The numeral 15 designates a pair of inclined tracks connected as indicated at 38 with the support 14, and connected as indicated at 16 with the auxiliary frame 5. The tracks 15 act as brakes for the support 14. The numeral 17 designates braces connected at their upper ends with the support 14 and connected at their lower 70 ends with the auxiliary frame 5.

At 18 there appears a conveyer frame provided adjacent its lower end with brackets 19 supporting for rotation, grooved rollers 20 adapted to traverse the tracks 15. Intermediate its ends, and at its sides, the conveyer frame 18 is equipped with guides, preferably in the form of rollers 21, engaging opposite edges of the braces 17. 75

Journalized in the lower end of the conveyer frame 18 is a drive shaft 22. The drive shaft 22 may be actuated in any desired way. In the present instance, a sprocket wheel 24 is secured to the shaft 22, and a chain 23 is trained around the sprocket 85 wheel. Adjacent its upper end, the conveyer frame 18 is provided at its sides with bearings 25 in which is journaled a shaft 26 carrying idle sprocket wheels 27. Journalized in the upper end of the conveyer 90 frame 18 is a shaft 28 provided with sprocket wheels 30. A conveyer belt 31 is trained around the sprocket wheels 30 and 32 and passes over the sprocket wheels 27. It will be obvious that the conveyer belt 31 95 may be actuated, to elevate the material, through the medium of the drive shaft 22.

Extended transversely of the support 14 and journaled thereon is a shaft 32 which may be actuated by means of a crank 33. Drums 100 34 are secured to the shaft 32. The lower ends of flexible elements 35 are connected with the drums 34, the flexible elements 35 being extended upwardly over sheaves 36 mounted to rotate on the support 14 near 105 to the upper end thereof. The flexible elements 35 are carried downwardly from the sheaves 36 and are secured as shown at 37 to the side portions of the conveyer frame 18.

From what has been explained hereinbefore, it will be obvious that by rotating the 110 shaft 8, the auxiliary frame 5, and the en-

tire conveyer mechanism carried thereby, may be caused to move longitudinally of the main frame 1 of the vehicle. By manipulating the flexible elements 35 by means 5 of the shaft 32, the upper end of the conveyer frame 18 may be raised and lowered. When the conveyer frame 18 is raised and lowered, the guides 21 coacting with the inclined tracks 17, will cause the conveyer 10 frame 18 to move transversely of the main frame 1 of the vehicle, the wheels 20 riding on the tracks 15.

Attention is directed to my copending application serial No. 101,376 for Letters Patent on a grain-stacking device, filed June 2, 1916. This present application serial No. 121,274 shows an improved form of stacker. I shall, therefore, claim my invention as broadly as possible in application No. 20 121,274, which shows the improved form, and in my earlier application I shall claim such structural features as distinguish the machine shown in the earlier application from the machine shown in this application 25 No. 121,274, the patent maturing out of application No. 121,274 being permitted to issue before the patent which results from application No. 101,376, or simultaneously therewith.

Copies of this patent may be obtained for five cents each, by addressing the "Commissioner of Patents, Washington, D. C."

Having thus described the invention, what is claimed is: —

In a device of the class described, a vehicle including a main frame; an auxiliary frame mounted to slide on the main frame, longitudinally of the main frame; means for 35 sliding the auxiliary frame on the main frame longitudinally of the main frame; a support upstanding from the auxiliary frame; an inclined track connecting the support with the auxiliary frame; a second 40 track inclined with respect to the vertical and connecting the support with the auxiliary frame; a conveyer frame; a conveyer carried by the conveyer frame; means mounted on the conveyer frame for engaging 45 the first specified track slidably; a guide carried by the conveyer frame and coacting with the second specified track to move the conveyer frame longitudinally; and means assembled with the support for raising and 50 lowering the conveyer frame.

In testimony that I claim the foregoing as my own, I have hereto affixed my signature in the presence of two witnesses.

THOMAS MAHONEY.
